UNITED STATES PATENT OFFICE.

JAMES MCRAE AND HAROLD INGRAM, OF LONDON, ENGLAND, ASSIGNEES TO HENRY FREDERIC DUCK, OF LONDON, ENGLAND.

ACETYLENE-GAS GENERATOR.

No. 866,049.

Specification of Letters Patent.

Patented Sept. 17, 1907.

Application filed March 23, 1906. Serial No. 307,564.

To all whom it may concern:

Be it known that we, JAMES MCRAE, civil engineer, and HAROLD INGRAM, engineer, both subjects of the King of Great Britain, residing, respectively, at 107 5 Cannon street, in the city of London, England, and 4 Cullum street, Fenchurch street, in the city of London, England, have jointly invented certain new and useful Improvements in Acetylene-Gas Generators, of which the following is a specification.

10 This invention relates to improvements in acetylene generators of the kind known as the "wet" system generators, in which the carbide of calcium is contained in a chamber at the bottom of a bell shaped vessel into which water contained in an outer tank can enter 15 or be forced out according to the pressure of the gas generated.

The object of the present invention is to enable the generation of the gas to be shut off at any moment during generation and to prevent after generation for any 20 desired period. It also provides for the automatic separation of the refuse and permits the unconsumed charge to be withdrawn at any period of the generating process for storage purposes and future use. To effect this purpose the carbide chamber is formed of a series of 25 compartments separated by wire disks which may be separately built up with supporting pieces in the center and placed in an outer shell, in order to let the parts be separately taken out for charging the carbide into the separate compartments, or the outer shell can be dis- 30 pensed with and the chamber be built up of wire gauze with separating disks provided with suitable doors at the side for charging.

The lowest compartment is always left empty but all the others being charged the apparatus is ready for 35 generation. On water being admitted to the bottom of the charging chamber it attacks the carbide contained in the second chamber, generating gas which rises through the other chambers to the gas outlet, the refuse in the meantime falling through the perforated 40 wire disk into the lowest chamber. On the gas being cut off for a time sufficient gas is generated to cause the water to be forced out of the bell in order to prevent its acting further on the carbide until required. Such carbide being also out of contact with the wet refuse, no 45 further gas is generated until required. The operation is repeated in connection with each compartment, each such acting as a refuse chamber for the next compartment above until the whole of the carbide has been utilized, when the apparatus can be recharged and operated 50 in a similar manner.

In the accompanying drawings Figure 1 is a central vertical section of the improved generator; Fig. 2 is a detail showing one method of building up the carbide chamber; and Fig. 3 a similar detail showing a modified construction of the carbide chamber.

Referring first to Fig. 1, within the water containing outer vessel *a* is a bell-shaped gas receiver *b* within which is the carbide chamber consisting of an outer shell or vessel *c*, which is open at the top and closed at the bottom except for an aperture or tube *d* communicating with the water vessel *a*, and a series of perforated trays *e*, placed one over the other, on which are stacked the lumps or blocks of calcium carbide *f*. The holes in the trays are of such size as to enable the calcium refuse as it is formed to pass through under its own weight or the pressure of the super-incumbent carbide into the receptacle formed by the lower part of the shell *c*, which should be of a capacity sufficient to accommodate the refuse of at least one tray charge of carbide.

70 The trays are preferably formed, as shown in Fig. 2, of wire gauze disks *e'*, the edges of which are clamped between and stiffened by metal rings *e*² which are provided with supporting legs *e*³. Handles *e*⁴ may be affixed to the trays for convenience in removing them from, and replacing them in the shell *c* when charging the chamber with carbide, or removing unspent carbide therefrom. Alternatively, the trays may be combined with the containing shell in an integral structure as shown in Fig. 3, in which case each compartment *e* is 80 provided with a side door *e*⁵ for charging or discharging purposes.

The gas delivery pipe *g* leading from the bell receiver *b* is suitably secured to the roof thereof and also to a strap or cover *h* which is detachably fixed over 85 the mouth of the water vessel *a* by any suitable means. The bell itself is further secured to the cover *h* by straps *i*. A cock *g'* in the delivery pipe controls the outflow of the gas.

When the carbide chamber is charged and the bell 90 secured in position as shown in Fig. 1 with the cock *g'* closed, the water placed in the outer vessel *a* enters the shell *c* through the pipe *d*, which is preferably closed at the top and has lateral openings to prevent choking with calcium refuse, but it is prevented from 95 reaching the carbide trays by the pressure of the air trapped and compressed within the bell, until the cock *g'* is opened, whereupon generation of gas begins, and proceeds at a rate corresponding to the consumption of the lamp or lamps supplied from the generator, a 100 diminution of consumption causing an increase of pressure in the bell and consequently causing the water to recede partly or entirely from contact with the carbide and correspondingly reducing the rate of generation.

So far the operation of the generator is in no way 105 different from wet system generators of known types, but the arrangement of trays above described which constitutes part of the present invention enables the spent and water logged calcium refuse to separate from the unspent carbide as it is formed and subside 110

through the water to the bottom of the vessel, so that when the cock is closed and the water recedes by virtue of the increase of gaseous pressure in the bell out of contact with the unspent carbid, there is little or none 5 of the water-logged refuse left in contact with the unspent carbid and consequently after-generation of gas from this cause is obviated.

Having thus described the nature of our said invention and the best means we know of carrying the 10 same into practical effect, we claim:—

1. A wet system acetylene generator comprising an outer water vessel, a bell-shaped gas receiver having its lower end sealed by the water in the outer vessel and an eduction tube at its upper end detachably secured to the said outer 15 vessel, a multi-stage carbid holder within the bell receiver having a plurality of carbid trays arranged one above the other and adapted to be separately charged, a refuse compartment under the bottom tray, having a solid base and an opening therein fitted with a laterally perforated vertical 20 cal tube, said tube being closed at its upper end and opening at its lower end into the outer water vessel; substantially as described.

2. A wet system acetylene generator comprising an outer water vessel, a bell-shaped gas receiver having its lower 25 end sealed by the water in the outer vessel and an eduction tube at its upper end detachably secured to the said outer vessel, a multi-stage carbid holder within the bell receiver having a plurality of superposed compartments each hav-

ing a door for the supply and withdrawal of the charge of calcium carbid and a reticulated grid supporting the carbid blocks, said reticulations forming a large proportion of the total area of the grid, a refuse compartment under the bottom tray, and means for allowing the passage of water in either direction between the water vessel and refuse chamber, while retaining the refuse within the said chamber; substantially as described. 30 35

3. A wet system acetylene generator comprising an outer water vessel, a bell-shaped gas receiver having its lower end sealed by the water in the outer vessel and an eduction tube at its upper end detachably secured to the said outer 40 vessel, a multi-stage carbid holder within the bell receiver having a plurality of superposed compartments each having a door for the supply and withdrawal of the charge of calcium carbid and a reticulated grid supporting the carbid blocks, said reticulations forming a large proportion of 45 the total area of the grid, and a refuse chamber located under the carbid compartments having a solid base and an opening therein fitted with a laterally perforated vertical tube, said tube being closed at its upper end and opening at its lower end into the outer water vessel; substantially as 50 described.

In testimony whereof we have signed our names to this specification in the presence of two subscribing witnesses.

JAMES MCRAE.
HAROLD INGRAM.
